SWIM FIN

Alexander A. Roman, 35 Meadowood Path,
New Rochelle, N.Y.

Filed Apr. 4, 1963, Ser. No. 74,294

Term of patent 14 years

(Cl. D71—1)

I claim:

The ornamental design for a swim fin, as shown.
